UNITED STATES PATENT OFFICE.

JOHN F. MALONE, OF BUFFALO, NEW YORK, ASSIGNOR TO BUFFALO FIRE PROOF LATH COMPANY, OF BUFFALO, NEW YORK, A CORPORATION OF NEW YORK.

METAL LATH.

SPECIFICATION forming part of Letters Patent No. 768,947, dated August 30, 1904.

Application filed February 6, 1904. Serial No. 192,321. (No model.)

To all whom it may concern:

Be it known that I, JOHN F. MALONE, a citizen of the United States, residing at Buffalo, in the county of Erie and State of New York, 5 have invented certain new and useful Improvements in Metal Laths, of which the following is a specification.

This invention relates to an improved form of metal lath, which is pressed or otherwise 10 formed from suitable sheet metal and is provided with a plurality of raised and depressed members arranged in rows and one or more corrugations extending throughout said members.

15 The object of the invention is to strengthen and stiffen the members throughout by forming therein continuous reinforcing-corrugations.

The invention also relates to certain novel 20 details of construction, all of which will be fully and clearly hereinafter described and claimed, reference being had to the accompanying drawings, in which a preferred adaptation of the lath is shown.

25 Figure 1 is a top plan or face view of a fragment of my preferred adaptation of my improved metal lath. Fig. 2 is a longitudinal section on line *a a*, Fig. 1. Fig. 3 is a longitudinal section on line *b b*, Fig. 1. Fig. 4 30 is a transverse section on line *c c*, Fig. 1. Fig. 5 is a transverse section on line *d d*, Fig. 1.

In referring to the drawings in detail like numerals designate like parts.

In the preferred adaptation of the invention 35 illustrated in the accompanying drawings the completed metal lath is formed so that both sides are practically the same, the raised members on one side constituting depressed members on the opposite side and the raised longitudinal ribs on one side forming longitudinal recesses upon the opposite side, thus making the lath reversible.

Viewing one face or side of a completed lath- 45 sheet, as shown in Fig. 1, it will be noted that it is provided with a series of members or parts 1 and 2, which are bent or faced outwardly from the plane of the sheet. These members are in longitudinal columns and in alternate

sequence—that is, for instance, with the members of the first longitudinal column raised 50 and the members of the next or second column depressed—so that the members of each longitudinal column extend opposite to the members of the immediately adjacent column on either or both sides. The members in each 55 longitudinal column are separated from each other by substantially flat portions 3. The raised and depressed members form a series of transverse rows with the raised and depressed members thereof located in alternate 60 arrangement and separated by longitudinal slits 4.

The raised and depressed members are strengthened and stiffened throughout by corrugations which extend through the metal-lath sheet. In the preferred adaptation these corrugations extend oppositely to the members through which they pass and are arranged in alternate sequence to correspond with the alternate arrangement of the members. In the adaptation illustrated the corrugations are in alternate pairs, with each pair extending longitudinally throughout the metal sheet and through one of the longitudinal rows and projecting oppositely to the 70 members of said rows, so that the raised or projecting members 1 are provided with one or more longitudinal recesses or grooves 5 in their projecting faces and the depressed members 2 with one or more longitudinal raised 75 or projecting ribs 6. It will be noted that the corrugations extend completely throughout the metal-lath sheet and form a series of continuous stiffening-ribs for the raised and depressed members 1 and 2 and the intervening 80 flat portions 3, so that the lath is strengthened and stiffened longitudinally throughout.

The lath is formed by first passing a substantially flat sheet through corrugating mechanism and then through slitting and lath-forming mechanism.

One of the great advantages of this improved lath is that the raised members are strengthened and stiffened entirely throughout by longitudinal corrugations, which also 95 form one or more narrow longitudinal re-

cesses on the projecting side or face of each raised member, in which a portion of the plaster can be locked completely across the face of the member, thereby locking or anchoring the plaster very securely to the sheet and likewise reinforcing the corrugations by longitudinal keys of plaster fitted snugly in the recesses.

I claim as my invention—

- 10 1. A metal lath having a series of alternate raised and depressed members separated by slits and a series of longitudinal corrugations arranged in alternate order and extending oppositely to the members through which they pass.
- 15 2. A metal lath having a series of alternate raised and depressed members separated by slits, and a series of longitudinal corrugations arranged in alternate pairs and with each pair

extending oppositely to the members through 20 which they pass.

3. A metal lath having a series of members separated by slits, and each member constituting a raised or projecting portion on one side of the plate and a depressed portion on 25 the opposite side of said plate and a series of corrugations extending throughout the lath, each of which forms a longitudinal projecting rib in the depressed portion on the side opposite to which the member itself projects and 30 a longitudinal recess extending completely throughout the projecting face of said member, substantially as set forth.

JOHN F. MALONE.
